(57) **CLAIM**

The ornamental design for a 360 degree conference microphone, as shown and described.

DESCRIPTION

FIG. 1 is a top perspective view of a 360 degree conference microphone;

FIG. 2 is a top view of the 360 degree conference microphone;

FIG. 3 is a bottom view of the 360 degree conference microphone;

FIG. 4 is a rear view of the 360 degree conference microphone

FIG. 5 is a front view of the 360 degree conference microphone;

FIG. 6 is a right side view of the 360 degree conference microphone; and,

FIG. 7 is a left side view of the 360 degree conference microphone.

Portions of the drawings shown in broken lines form no part of the claimed design.
